US00D856703S

(12) **United States Design Patent** (10) **Patent No.:** **US D856,703 S**
(45) **Date of Patent:** **** Aug. 20, 2019**

(54) **MAT**

(71) Applicant: **Loctek Inc.**, Livermore, CA (US)

(72) Inventors: **Lehong Xiang**, Ningbo (CN); **Haoyu Ye**, Ningbo (CN); **Xinbo Zhang**, Ningbo (CN)

(73) Assignee: **Loctek Inc.**, Livermore, CA (US)

(**) Term: **15 Years**

(21) Appl. No.: **29/633,586**

(22) Filed: **Jan. 15, 2018**

(30) **Foreign Application Priority Data**

Jul. 18, 2017 (CN) 2017 3 0318185

(51) **LOC (12) Cl.** **06-11**

(52) **U.S. Cl.**
